UNITED STATES PATENT OFFICE.

PHILLIPP F. FLAGGE, OF GREEN BAY, WISCONSIN.

ILLUMINATED CRUCIFIX.

1,391,945.

Specification of Letters Patent. Patented Sept. 27, 1921.

Application filed March 8, 1921. Serial No. 450,767.

To all whom it may concern:

Be it known that I, PHILLIPP F. FLAGGE, a citizen of the United States, and resident of Green Bay, in the county of Brown and State of Wisconsin, have invented certain new and useful Improvements in Illuminated Crucifixes; and I do hereby declare that the following is a full, clear, and exact description thereof.

10 My invention refers to illuminated ornaments and particularly crucifixes for decoration, the same being designed for the purpose of illuminated cap ornaments for churches or the like.

15 The object of my invention is to provide a simple, durable and cheaply manufactured illuminated crucifix for the above purpose, whereby economy in illumination will result, as well as economy and durability in structure.

20 A specific object of my invention is to provide a metallic frame for a cross composed of inturned channel iron for the vertical side walls of the cross stem, and its 25 cross arms, which channels are adapted to have affixed thereto glass panels that are secured to the inturned flanges of the channel irons.

25 Another object of my invention is to provide reflector units which are fitted to the base and top of the cross stem, and also ends of its cross arms, in such relation that a single lamp associated with the base reflector will diffuse light throughout the structure.

30 Another object of my invention is to provide cap units for the top of the cross stem and cross arms, together with a standard for supporting the base of the cross stem, which base is incased within a cap that springs 35 from the standard whereby these parts are securely anchored and protected.

35 With the above and other minor objects in view, the invention consists in certain peculiarities of construction and combination 40 of parts, as are hereinafter set forth with reference to the accompanying drawing and subsequently claimed.

In the drawings:

45 Figure 1 represents a face view of a crucifix embodying the features of my invention, with parts broken away and in section to more clearly illustrate details of construction, and

50 Fig. 2 is a cross section of the same, the section being indicated by line 2—2 of Fig. 1.

Referring by characters to the drawing, 1

represents a standard, in this case being shown in the form of a turret or tower, the end of which is provided with a globular cap 2. The skeleton of the tower is formed 60 from a series of converging beams 1', and fitted to the beams and the mouth of the cap 2 are parallel I-beams 3—3 having inturned flanges as shown. The I-beams are arranged 65 parallel and form vertical side walls of the stem of a cross. The channel irons are intersected near their upper ends by horizontal channelled sections 4—4 forming the cross arms of a skeleton frame of the crucifix. The channel irons 3 and 4 have secured 70 thereto front and rear face plates 5—5, which comprise glass panels whereby the structure is rendered transparent as to its faces and is rectangular in cross section, being closed to atmospheric conditions. The 75 open ends of the cross arms and top of the stem have secured therein cupped reflectors 6—6 and 6' respectively, and the base of the cross stem is fitted with a similar master reflector 7. The master reflector is provided 80 with a lamp 7' which is fed from a suitable source of electric power, whereby the illumination of the cross structure is effected.

The ends of the cross arms and top of the stem have fitted thereto companion caps 85 8—8 8' respectively, whereby the reflectors are incased and the cross ends are thus effectually sealed against climatic conditions. It is understood that these caps are secured 90 to the channel iron by supporting welding 90 brazed or other convenient means.

From the foregoing description, it will be seen that when the device is in operation, the single lamp associated with the master reflector will diffuse light throughout the 95 stem and cross arms, which light is reflected and diffused between series of reflectors at the arm ends of the crucifix and thus a series of lamps is dispensed with for effecting the desired illumination.

100 It is further understood that the single lamp employed for effecting the illumination of the entire structure is concealed, whereby a soft glow throughout the cross will result, which glow is magnified, due to the counter reflections from the different deflectors. Thus, it will be seen that an illuminated cross is designed wherein standard channels may be used, and the cost of manufacture is materially reduced, and further 105 more standard caps can be employed for finishing the ends of the cross, which caps 110

not only serve as strengthening elements for the structure, but also as closures for the open ends of the skeleton frame, whereby all parts are thoroughly protected. It will be observed that owing to the interlocked construction between the base of the cross and the standard, said cross is rigidly maintained in the desired position and will resist wind pressures or the like. Obviously the channel iron side plates may, in some instances, be in the form of skeleton structures and reflecting mirror plates may be inserted in the side walls, similar to the plates shown in the front and rear face of the crucifix.

I claim:

1. As a new article of manufacture, an illuminated cross comprising a frame including vertically disposed side panels formed from metallic inturned channel irons constituting the stem of a cross, the vertical channel irons being intersected by horizontal channel iron sections constituting the cross arms, cupped reflectors fitted into the upper end of the stem and ends of the cross arm between the channel irons, front and rear glass panels fitted and secured to the inturned flanges of the channel irons of said stem and cross arms, a cross supporting standard means for securing the base of the cross to the standard including

a base cap incasing the lower ends of said stem, a master reflector fitted into the base of the cross stem, a lamp nested in the master reflector adapted to diffuse light throughout the cross structure from the master reflector and the associated series of reflectors at the upper end of the stem and at the ends of the cross arms, and caps incasing the channel irons and reflectors at the ends of the cross arms and the top of the stem.

2. An illuminated cross comprising a standard, metallic side panels extending from the standard, the same being merged into parallel horizontal sections to form cross arms, front and rear glass plates fitted to the flanges of the channel irons, a master reflector at the base of the cross stem, other reflectors at the ends of the cross arms and the top of the stem, and a lamp nested within the base reflector for diffusing light throughout the cross structure in conjunction with the series of reflectors at the top of the stem and the ends of the aforesaid cross arms.

In testimony that I claim the foregoing I have hereunto set my hand at Green Bay, in the county of Brown and State of Wisconsin.

PHILLIPP F. FLAGGE.
